(57) **CLAIM**

The ornamental design for a vacuum cleaner, as shown and described.

DESCRIPTION

1. Vacuum cleaner
- 1.1 is a perspective view of the vacuum cleaner showing my new design;
- 1.2 is a perspective view thereof, showing the handle portion in an alternate position;
- 1.3 is a front elevation view thereof;
- 1.4 is a side elevation view thereof; and
- 1.5 is a rear elevation view thereof.
